UNITED STATES PATENT OFFICE.

JOSEPH BRIELOFF, OF BROOKLYN, NEW YORK, ASSIGNOR TO SUN-RAY LIGHTING PRODUCTS, INC., OF NEW YORK, N. Y.

DESIGN FOR A DESK LAMP.

Application filed June 8, 1927. Serial No. 22,364. Term of patent 7 years.

To all whom it may concern:

Be it known that I, JOSEPH BRIELOFF, a citizen of the United States, residing at 1690 President Street, Brooklyn, in the county of Kings and State of New York, have invented a new, original, and ornamental Design for Desk Lamps, of which the following is a specification, reference being had to the accompanying drawing, forming part thereof.

The figure is a front perspective view of a desk lamp, showing my new design.

I claim:

The ornamental design for a desk lamp, as shown.

JOSEPH BRIELOFF.
